CLAIM

The ornamental design for a blood infusion box, as shown and described.

DESCRIPTION

FIG. 1 is a left front perspective view of a blood infusion box showing my new design;

FIG. 2 is a rear elevation view thereof;

FIG. 3 is a bottom view thereof;

FIG. 4 is a top view thereof;

FIG. 5 is a left elevational view thereof; and

FIG. 6 is a right elevational view thereof.

The hose is broken away in the drawing views to indicate indeterminate length.

FIG. 4

FIG. 5

FIG. 6
